Int. Cl. D5—02

U.S. Cl. D92—1

FIG-1

FIG. 2

FIG. 1 is a top plan view of a textile fabric showing my new design; and

FIG. 2 is an enlarged view of a fragmentary portion of FIG. 1 more fully illustrating the wavy ribbed background thereof.

The characteristic feature of my design resides in the combination on a textile fabric of zig-zag lines, and wavy lines, the wavy lines extending through the zig-zag lines and in the same general direction, all as best shown in FIG. 2.

I claim:

The ornamental design for a textile fabric, substantially as shown and described.
